(No Model.)

T. B. HOWE.

CAR STEP.

No. 274,197.

Patented Mar. 20, 1883.

UNITED STATES PATENT OFFICE.

THOMAS B. HOWE, OF SCRANTON, PENNSYLVANIA.

CAR-STEP.

SPECIFICATION forming part of Letters Patent No. 274,197, dated March 20, 1883.

Application filed January 30, 1883. (No model.)

To all whom it may concern :

Be it known that I, THOMAS B. HOWE, of Scranton, in the county of Lackawanna and State of Pennsylvania, have invented certain new and useful Improvements in Extensible Steps for Car-Platforms; and I do hereby declare the following to be a full, clear, and exact description of the same, reference being had to the accompanying drawings, forming 5 part of this specification, and to the figures and letters of reference marked thereon.

The object of this invention is to provide an additional step or steps for car-platforms, which can be lowered below the ordinary steps, 15 so as to form a continuation of the same, when desired, and which, when raised, shall be locked automatically in raised position.

To this end the invention consists in a novel construction, which I will now proceed to describe.

Referring to the accompanying drawings, Figure 1 represents a front elevation of car-steps provided with my extensible step, and Fig. 2 is a side elevation of the same.

Similar letters of reference in the several figures denote the same parts.

A represent the ordinary steps of a railway passenger-car.

B represents my supplemental step, the same being secured to side bars, C C, which pass up diagonally through slots S in the steps proper, and have turned-down or flanged upper ends, d, which, when the supplemental step is lowered, bear upon one of the steps and 35 serve to sustain the supplemental step in position, as shown in Fig. 2.

Secured to the supplemental step B, and extending upward therefrom, is a spring-rod, E, formed with a locking-shoulder, e, and an inclined portion, f. When the supplemental step is raised from a lowered position the inclined portion of the spring-rod strikes against the back edge of the step A next above it and causes the rod to bend backward until the shoulder e is reached, when it springs forward again and projects the said shoulder e over onto the step, thus forming a secure connection and maintaining the supplemental step in elevated position. To lower the step it is only necessary to press back the spring-rod until its shoulder is disengaged, and then the supplemental step will drop of its own weight or by a slight pull upon it.

I have shown but one extensible step, but

it is obvious that more than one may be employed.

It will be observed that when the supplemental step is raised it fits neatly under the lowest permanent step and is hardly noticeable.

The utility of my invention will be at once apparent. By lowering the step passengers are enabled to pass off and on the cars with ease, and without having to take a long step between the lowest permanent step and the 65 ground, as ordinarily. Before the train starts the step is raised up, and it automatically locks itself in raised position.

In order to prevent the foot of a passenger from accidentally striking against the spring-catch and disengaging it in ascending the steps when the supplemental step is in raised position, I provide the step with which the catch engages with a projecting plate, p, arranged in front of the catch and high enough 75 to arrest the foot of a passenger, but not so high as to prevent the train-hand from conveniently pressing back the spring-catch to disengage it, when desired.

To the rear edge of the extensible step I 80 also preferably secure a back plate, r, for the purpose of preventing the passenger's foot from slipping back through between the steps and subjecting him to the liability of a painful accident, as well as to guard against the 85 casual unlocking of the spring-catch.

I claim as my invention—

1. The combination, with the permanent car-steps, of the extensible supplemental step, the supporting side bars, and the automatic 90 locking-catch E, secured to and moving with the movable supplemental step, and having the shoulder adapted to engage with one of the permanent steps, substantially as described.

2. The combination, with the permanent 95 steps, of the movable supplemental step and its supporting side bars, and the guard-plate r, attached to and moving with the supplemental step, substantially as described.

3. The combination, with the permanent 100 steps, of the supplemental step, the automatic spring-catch, and a guard on the permanent step for preventing the accidental unlocking of the catch, substantially as described.

THOMAS B. HOWE.

Witnesses:

A. L. BAKER,
HENRY A. KNAPP.
